(57) **CLAIM**

The ornamental design of a passive heat sink stand for electronic devices, as shown and herein described.

DESCRIPTION

FIG. 1 is a top plan view of a passive heat sink stand for electronic devices showing my new design;

FIG. 2 is a bottom elevational view thereof;

FIG. 3 is a front elevational view thereof;

FIG. 4 is a rear elevational view thereof;

FIG. 5 is a side elevational view thereof;

FIG. 6 is an opposing side elevational view thereof;

FIG. 7 is a partial perspective view from the top thereof;

FIG. 8 is a cut-away side view taken along line 8—8 of FIG. 7;

FIG. 9 is a partial perspective view from the bottom thereof;

FIG. 10 is a top perspective view thereof; and,

FIG. 11 is a top perspective view as illustrated in combination with a computer.

The broken lines shown in the drawings are for illustrative purposes only and do not form part of the claimed design.
